United States Patent Office

Des. 189,230
Patented Nov. 8, 1960

189,230

FLOCKED TEXTILE FABRIC

Natalie Leavy, Clifton, N.J., assignor to Decorative Fabrics Company Incorporated, Pawtucket, R.I., a corporation of Rhode Island

Filed July 5, 1960, Ser. No. 61,221

Term of patent 14 years

(Cl. D92—1)

The figure is a plan view of a flocked textile fabric, showing my new design. A full width is shown vertically and the design repeats horizontally.

I claim:

The ornamental design for a flocked textile fabric, as shown and described.
